US007526736B2

(12) **United States Patent**
Kaminkow et al.

(10) **Patent No.:** **US 7,526,736 B2**
(45) **Date of Patent:** ***Apr. 28, 2009**

(54) **GAMING DEVICE HAVING TOUCH ACTIVATED ALTERNATING OR CHANGING SYMBOL**

(75) Inventors: **Joseph E. Kaminkow**, Reno, NV (US);
Aaron T. Jones, Reno, NV (US)

(73) Assignee: **IGT**, Reno, NV (US)

(*) Notice: Subject to any disclaimer, the term of this patent is extended or adjusted under 35 U.S.C. 154(b) by 554 days.

This patent is subject to a terminal disclaimer.

(21) Appl. No.: **10/826,465**

(22) Filed: **Apr. 16, 2004**

(57) **ABSTRACT**

A gaming device that enables a player to choose or alter certain symbols displayed on the reels of the gaming device. The player can change or select the changeable symbol at any time as long as the reels are not in motion. The gaming device maintains the change until the player changes the symbol again. The gaming device preferably supplies a touch screen along with a video monitor in which the reels and associated stops are simulated. The touch screen enables the player to simply touch the symbol that the player wishes to change. Pressing a single symbol may change the selected symbol or others linked to the symbol. A stop on the reels having a selectable symbol can provide the player with any number of possible symbols from which to choose. The changeable symbols preferably have a direct effect upon whether the player obtains a gaming device award.

GAMING DEVICE HAVING TOUCH ACTIVATED ALTERNATING OR CHANGING SYMBOL

PRIORITY CLAIM

This application is a continuation application of U.S. patent application Ser. No. 09/602,331, filed Jun. 23, 2000, now U.S. Pat. No. 6,731,313 entitled "Gaming Device Having Touch Activated Alternating Or Changing Symbol."

CROSS-REFERENCE TO RELATED APPLICATIONS

This application is related to the following commonly-owned patent applications: "GAMING DEVICE WITH TRAVELING REEL SYMBOLS," Ser. No. 09/689,197, now U.S. Pat. No. 6,565,433; "GAMING DEVICE WITH MOVING SCREEN SIMULATION," Ser. No. 09/625,884, now U.S. Pat. No. 6,837,790; "GAMING DEVICE PROVIDING TOUCH ACTIVATED SYMBOL INFORMATION," Ser. No. 09/680,349, now U.S. Pat. No. 6,939,223; "GAMING DEVICE HAVING INTERACTING SYMBOLS," Ser. No. 09/686,308, now U.S. Pat. No. 6,981,635; "GAMING DEVICE HAVING CHANGED OR GENERATED PLAYER STIMULI," Ser. No. 09/686,244, now U.S. Pat. No. 6,739,973; "GAMING DEVICE HAVING INDEPENDENT REEL COLUMNS," Ser. No. 10/165,260, now U.S. Pat. No. 7,001,274; "GAMING DEVICE WITH A BONUS SCHEME HAVING REPEATED SELECTION OF VALUE SETS WITH OPTION TO SAVE VALUES," Ser. No. 10/231,639, now U.S. Pat. No. 7,229,350; "GAMING DEVICE WITH TRAVELING REEL SYMBOLS," Ser. No. 10/409,965, "GAMING DEVICE WITH TRAVELING REEL SYMBOLS," Ser. No. 10/409,727, now U.S. Pat. No. 6,918,832; "GAMING DEVICE HAVING A CASH OUT MENU SCREEN AND A SYSTEM AND METHOD FOR ENABLING A PLAYER TO RETRIEVE MONEY FROM A GAMING DEVICE," Ser. No. 10/439,357, now U.S. Pat. No. 6,835,134; "GAMING DEVICE HAVING MULTIPLE SELECTABLE DISPLAY INTERFACES," Ser. No. 10/659,093, "GAMING DEVICE WITH MULTI-PURPOSE REELS," Ser. No. 10/023,268, now U.S. Pat. No. 6,702,675; "GAMING DEVICE HAVING A CASH OUT MENU SCREEN AND A SYSTEM AND METHOD FOR ENABLING A PLAYER TO RETRIEVE MONEY FROM A GAMING DEVICE," Ser. No. 10/767,243, "GAMING DEVICE HAVING INDEPENDENT REEL COLUMNS," Ser. No. 11/327,803, now U.S. Pat. No. 7,309,281; "GAMING DEVICE HAVING INDEPENDENT REEL COLUMNS," Ser. No. 11/326,787 "GAMING DEVICE HAVING INDEPENDENT REEL COLUMNS," Ser. No. 11/355,304, now U.S. Pat. No. 7,309,282; "GAMING DEVICE HAVING CHANGED OR GENERATED PLAYER STIMULI," Ser. No. 10/841,014, now U.S. Pat. No. 7,258,613; "GAMING DEVICE HAVING MULTIPLE SELECTABLE DISPLAY INTERFACES BASED ON PLAYER'S WAGERS," Ser. 15

DESCRIPTION

The present invention relates in general to a gaming device, and more particularly to a gaming device that enables a player to change or alter certain symbols displayed on the reels of the gaming device, which form random combinations of symbols that may yield an award.

20

BACKGROUND OF THE INVENTION

Gaming device manufacturers have long provided gaming machines employing a plurality of reels, wherein the reels each have a plurality of symbols. In the 1930's, gaming device manufacturers provided a three reel gaming device, wherein each reel had ten stops, which produced a thousand combinations. One way for the manufacturers to increase the number of combinations was to increase the size of the reel and to add more stops. During the next four decades, the reels in the gaming devices increased to twenty stops. In the 1970's, manufacturers developed a twenty-two stop reel machine, in the early 80's a twenty-five stop reel machine, and in 1985, IGT, the assignee of the present invention, developed a thirty-two stop reel machine. This three-reel machine had 32,768 possible combinations.

Another way manufacturers increased the number of combinations was to add reels. In 1955, a manufacturer produced a four-reel slot machine, which increased the number of combinations on a twenty stop machine to 160,000. In the middle 1970's, a manufacturer produced the first five-reel slot machine, which had twenty-two stop reels and produced combinations in excess of five million.

The next advancement in the effort to produce more payout combinations was the video or CRT screen slot machine, wherein the reels were simulated as opposed to mechanical. Video slot machines do not have mechanical drums or reels which rotate, do not need to precisely stop the same at certain positions and are therefore not limited by a maximum allowable drum radius. Each reel can have an unlimited number of stops. Initially, the Nevada gaming Commission limited the stops on the video machines (e.g., 84 stops on a three reel machine) but has since removed the limit. In 1989, a particular video reel machine employed reels having hundreds of stops and more than 10 million combinations.

The total number of combinations affects the percentage of time that a player will obtain a particular winning combination as well as the overall payout percentage of the machine. For example, a three reel machine having twenty-two stops per reel, wherein the first reel has two oranges, the second reel has three oranges, and the third reel has seven oranges will yield an orange, orange and orange combination 42 times in every 10,648 plays (22×22×22) or 0.39% of the time. If the orange, orange, orange combination pays 20 coins, then the total coins paid is 20×42 or 840 coins in every 10,648 plays.

Adding the total coins paid for each winning combination and dividing that number by 10,648 yields the machine's total payout percentage.

It should be appreciated that in the known gaming systems, the percentage of obtaining a winning combination is predetermined. In certain known progressive gaming machines, the payout of a grand prize grows each time a player plays the machine. The increasing payout increases the total coins paid as determined above, which in turn increases the overall payout percentage. Nevertheless, the percentage of times that a player will receive one of the combinations remains constant.

To increase player enjoyment and excitement, it is desirable to provide players with new types of gaming devices that attract the player and keep the player entertained. One way to hold a player's interest is to vest the player with the ability to affect the determination of the outcome. That is, to give the player a stake or "say so" in the manner in which the gaming device determines the player's outcome. Certain known gaming devices have bonus rounds, wherein a player selects the player's own fate. For example, European Patent Application No. EP 0 945 837 A2 filed on Mar. 18, 1999 and assigned on its face to WMS Gaming, Inc. discloses a gaming device having a bonus round, wherein a player chooses a masked symbol from a pattern of symbols, and the gaming device removes the mask and either awards the player with a bonus value or terminates the bonus round with a bonus terminator. The player chooses until selecting a bonus terminator. However, known gaming devices have yet to add similar player selectivity to the base game or reel operation of the gaming device.

SUMMARY OF THE INVENTION

The present invention overcomes the above shortcomings by enabling the player to choose or alter certain symbols displayed on the reels of the gaming device. The reels of a gaming machine, even in video form, each contain a set number of stops. Of those stops, the present invention designates or assigns certain stops to have changeable symbols. In a multiple reel gaming device, each reel may or may not have one or more changeable symbols.

The present invention enables the player to change or select the changeable symbol at any time as long as the reels are not in motion. The present invention contemplates letting a potential player who has yet to place money in the gaming device toggle through and peruse the various selections that the player can make. While playing the device, the player can select or change a changeable symbol at any time, and the gaming device maintains the change until the player (or another player) changes the symbol again.

The present invention preferably provides a touch screen video monitor in which the reels and associated stops are simulated. The touch screen enables the player to simply touch the symbol that the player wishes to change. Alternatively, the gaming device can provide a bare video monitor or television screen that merely displays the symbols. In this embodiment, the gaming device provides extra input devices such as push-buttons that enable the player to toggle through the selection of changeable symbols.

The gaming device contemplates the act of pressing a single changeable symbol or pushbutton having a plurality of effects. One effect that the act of pressing a symbol or button has is to change the selected symbol and nothing more. In this embodiment, each changeable symbol is individually selectable. In other embodiments, one or more changeable symbols are linked. For example, in one embodiment, changing a symbol changes all like symbols on the same reel. In another

embodiment, changing a symbol changes all like symbols on the same payline. In a further embodiment, changing a symbol changes all like symbols displayed on the video monitor. In a still further embodiment, changing a symbol changes all like symbols on everyone of the stops of the gaming device.

A stop having changeable symbols may have two or more possibilities. That is, a person may toggle through and select from two, three, four, or any number of possible symbols that the implementor wishes to provide. Different stops can have different symbols and a different number of symbols from which to choose. Preferably, the choices follow a theme that the gaming device employs. For example, one embodiment of the present invention contains symbols relating to oriental food dishes and drinks. The gaming device enables the player to toggle or change between a "MSG" symbol or a "NO MSG" symbol. The player can therefore select which symbol with which the player desires to play the game.

The present invention preferably provides an audio display or production that coincides with the change or selection of a new symbol. The production can prompt the player, e.g., "Would you like "MSG" or "NO MSG"?" Alternatively, the production can acknowledge a player's choice e.g., "MSG, NO MSG, You have selected NO MSG." A separate video display or screen on the video monitor can enhance or increase enjoyment through a suitable demonstration that corresponds to a symbol change.

At least one and preferably a greater percentage of the winning combinations of symbols maintained by the gaming device contain at least one changeable or selectable symbol. In this way, changing the symbol has a direct affect upon whether the player succeeds and wins an award. The changeable symbols also enable the player to establish personal preferences on the symbols, which vest the player in the outcome of the gaming device and provide additional enjoyment and entertainment for the player.

It is therefore an object of the present invention to provide a gaming device that enables a player to change one or more symbols on a random outcome generating reel of a gaming device.

Another object of the present invention is to enable the player to make selections that directly affect the outcome of playing the gaming device.

Yet another object of the present invention is to vest the player in the gaming device by enabling said player to establish personal preferences through the selection of changeable symbols.

Other objects, features and advantages of the invention will be apparent from the following detailed disclosure, taken in conjunction with the accompanying sheets of drawings, wherein like numerals refer to like parts, elements, components, steps and processes.

BRIEF DESCRIPTION OF THE DRAWINGS

FIG. 1 is a front plan view of the general configuration of the gaming device of the present invention;

FIG. 2 is a schematic block diagram of the electronic configuration of one embodiment of the gaming device of the present invention;

FIG. 3 is a front plan view of one embodiment of the gaming device of the present invention that illustrates a touch screen video monitor with a plurality of selectable or changeable reel stops;

FIG. 4 is front plan view of one embodiment of the display of the video monitor of the gaming device having selectable or changeable reel stops;

FIG. 5 is a front plan view of another embodiment of the display of the video monitor of the gaming device having selectable or changeable reel stops;

FIG. 6 is a front plan view of a further embodiment of the display of the video monitor of the gaming device having selectable or changeable reel stops; and

FIG. 7 is a top plan view of five reel strips having a plurality of stops which contain changeable symbols.

DETAILED DESCRIPTION OF THE INVENTION

Gaming Device and Electronics

Referring now to the drawings, FIG. 1 generally illustrates a gaming device 10 of one embodiment of the present invention, which is preferably a slot machine having the controls, displays and features of a conventional slot machine. Gaming device 10 is constructed so that a player can operate gaming device 10 while standing or sitting. However, it should be appreciated that gaming device 10 can be constructed as a pub-style table-top game (not shown) that a player can operate preferably while sitting. Gaming device 10 can also be implemented as a program code stored in a detachable cartridge for operating a hand-held video game device. Also, gaming device 10 can be implemented as a program code stored on a disk or other memory device which a player can use in a desktop or laptop personal computer or other computerized platform. Gaming device 10 can incorporate any game such as slot, poker or keno. The symbols used on and in gaming device 10 may be in mechanical, electrical or video form.

As illustrated in FIG. 1, gaming device 10 includes a coin slot 12 and bill acceptor 14 where the player inserts money, coins or tokens. The player can place coins in the coin slot 12 or paper money in the bill acceptor 14. Other devices could be used for accepting payment such as readers or validators for credit cards or debit cards. When a player inserts money in gaming device 10, a number of credits corresponding to the amount deposited is shown in a credit display 16. After depositing the appropriate amount of money, a player can begin the game by pulling arm 18, pushing play button 20. Play button 20 can be any play activator used by the player which starts any game or sequence of events in the gaming device.

Referring to FIG. 1, gaming device 10 also includes a bet display 22 and a bet one button 24. The player places a bet by pushing the bet one button 24. The player can increase the bet by one credit each time the player pushes the bet one button 24. When the player pushes the bet one button 24, the number of credits shown in the credit display 16 decreases by one, and the number of credits shown in the bet display 22 increases by one.

Gaming device 10 also has a display window 28 which contains a plurality of reels 30, preferably three to five reels in mechanical or video form. Each reel 30 displays a plurality of symbols such as bells, hearts, martinis, fruits, cactuses, numbers, cigars, letters, bars or other images which preferably correspond to a theme associated with the gaming device 10. If the reels 30 are in video form, the gaming device 10 preferably displays the video reels 30 at video monitor 32 instead of at display window 28. Furthermore, gaming device 10 preferably includes speakers 34 for making sounds or playing music.

At any time during the game, a player may "cash out" and thereby receive a number of coins corresponding to the number of remaining credits by pushing a cash out button 26. When the player "cashes out," the player receives the coins in a coin payout tray 36. The gaming device 10 may employ

other payout mechanisms such as credit slips redeemable by a cashier or electronically recordable cards which keep track of the player's credits.

With respect to electronics, the controller of gaming device 10 preferably includes the electronic configuration generally illustrated in FIG. 2, which has: a processor 38; a memory device 40 for storing program code or other data; a video monitor 32 or other display device (i.e., a liquid crystal display); a plurality of speakers 34; and at least one input device 10 as indicated by block 33. The processor 38 is preferably a microprocessor or microcontroller-based platform which is capable of displaying images, symbols and other indicia such as images of people, characters, places, things and faces of cards. The memory device 40 can include random access memory (RAM) 42 for storing event data or other data generated or used during a particular game. The memory device 40 can also include read only memory (ROM) 44 for storing program code which controls the gaming device 10 so that it plays a particular game in accordance with applicable game rules and pay tables.

As illustrated in FIG. 2, the player preferably uses the input devices 33, such as the arm 18, play button 20, the bet one button 24 and the cash out button 26 to input signals into gaming device 10. Furthermore, it is preferable that touch screen 46 and an associated touch screen controller 48 are used instead of a conventional video monitor 32. Touch screen 46 and touch screen controller 48 are connected to a video controller 50 and processor 38. A player can make decisions and input signals into the gaming device 10 by touching touch screen 46 at the appropriate places. As further illustrated in FIG. 2, the processor 38 can be connected to coin slot 12 or bill acceptor 14. The processor 38 can be programmed to require a player to deposit a certain amount of money in order to start the game.

It should be appreciated that although a processor 38 and memory device 40 are preferable implementations of the present invention, the present invention can also be implemented using one or more application-specific integrated circuits (ASIC's) or other hard-wired devices, or using mechanical devices (collectively referred to herein as a "processor"). Furthermore, although the processor 38 and memory device 40 preferably reside on each gaming device 10 unit, it is possible to provide some or all of their functions at a central location such as a network server for communication to a playing station such as over a local area network (LAN), wide area network (WAN), Internet connection, microwave link, and the like. For purposes of describing the invention, the controller includes the processor 38 and memory device 40.

Referring to FIGS. 1 and 2, to operate the gaming device 10, the player must insert the appropriate amount of money or tokens at coin slot 12 or bill acceptor 14 and then pull the arm 18 or push the play button 20. The reels 30 will then begin to spin. Eventually, the reels 30 will come to a stop. As long as the player has credits remaining, the player can spin the reels 30 again. Depending upon where the reels 30 stop, the player may or may not win additional credits.

Gaming Device Apparatus

Referring to FIG. 3, the present invention preferably employs a video monitor 32 having a touch screen 46 and touch screen controller 48 (shown in FIG. 2). Therefore, FIG. 3 does not display the display window 28 described with respect to FIG. 1. Accordingly, the video reels 30 are displayed in the video monitor 32. The embodiment displayed in FIG. 3 has five reels 30a, 30b, 30c, 30d, and 30e. The present

invention contemplates providing any number of reels, preferably, the present invention provides three to five reels.

The embodiment displayed in FIG. 3 also has three paylines 52a, 52b, and 52c. This embodiment shows a known type of gaming machine called a "line machine" which has multiple paylines which display a plurality of rows of symbols from the reels 30 as illustrated in FIG. 3. The line machines are distinguishable from the gaming machine displayed in FIG. 1 that has only one row of symbols or one payline. The multiple rows present multiple opportunities for the player to obtain a winning combination of symbols. Usually, players have to bet or pay more to obtain the benefit of the multiple lines. For illustration purposes, the present invention is described in connection with a line machine, however, the present invention contemplates employing single payline machines such as shown in FIG. 1.

Referring now to FIG. 4, an enlarged video screen 32 having a touch screen 46 and a touch screen controller 48 (shown in FIG. 2) displays the reels 30a through 30e and the paylines 52a through 52c described above. Each reel displays a plurality of symbols 54. For example, reel 30e displays the symbols 54a, 54b and 54c. The present invention contemplates enabling the player to change one or more of the symbols 54. Preferably, the present invention enables the player to change like symbols regardless of the reel on which they appear. For example, in one embodiment the present invention enables the player to change the "MSG" symbol 54b on reel 30e. The player can likewise change the "MSG" symbols 54b on the reel 30b.

In this embodiment, the present invention only enables the player to change the "MSG" symbol 54b, and its counterpart described below. However, the present invention contemplates enabling the player to change a plurality of symbols. For example, the present invention contemplates enabling the player to change the "DOUBLE DRAGON" symbol 54c as well as the "MSG" symbol. The implementor of the gaming device can enable a player to change any number of symbols in accordance with the gaming device theme and the payout structure of the gaming device.

Referring now to FIG. 5, the same enlarged video screen 32 as in FIG. 4 is shown displaying the changed symbol 154b. The symbol 154b displays the text "NO MSG." The preferred embodiment of the present invention contains a theme, wherein the game displays oriental items including oriental food and gives the player a choice between having "MSG" or "NO MSG." The theme distinguishes the choices that are provided. It should be appreciated that the present invention does not have to provide a theme. The choices can be completely unrelated to each other. For example, the counterpart to the "MSG" symbol 54b can be the "DOUBLE DRAGON" symbol 54c.

In accordance with the theme of the gaming device, the present invention preferably provides an audio display that accompanies the player's decision to change one of the symbols 54. For example, in the preferred embodiment, the gaming device emits a voice having the characteristics of an oriental man from the speakers 34 when the player changes the "MSG" symbol 54b or the "NO MSG" symbol 154b. When the player changes the "MSG" symbol, the speakers emit the voice of an oriental man saying the letters, "M-S-G." Likewise, when the player changes the "NO-MSG" symbol 154b, the speakers emit the voice saying, "NO-MSG." This provides the player with an entertaining aside from playing the game.

It should be appreciated that the gaming device can provide an audio display before and after the player changes a symbol. For example, the gaming device can, after every spin of the

reels, prompt the player with a suitable message such as, "MSG or NO-MSG?". The present invention can provide any suitable sound and is not limited to reciting the text of the symbol.

5 The invention also contemplates providing a visual display either before, after or contemporaneous with a symbol change. The video display 32 or some other suitable display can produce the visual display, which preferably corresponds with the theme of the gaming device. For example, the present 10 invention can have a separate display of a fictitious blood pressure indicator that fluctuates depending upon whether the player selects "MSG" or "NO-MSG."

Referring now to FIGS. 4 and 5, the present invention preferably includes a touch screen 46 with the video display 32. The touch screen 46 of the video display 32 enables the player to command the game to perform many functions. The collect button 56 enables the player to cash out. The help button 58 enables the player to receive instructions. The "see pays" button 60 enables the player obtain payout information. 15 The "select lines" button 62 enables the player to activate different paylines 52. The "bet per line" button 64 enables the player to modify the player's bet for each payline 52. The "max bet spin" button 66 enables the player to bet the maximum amount and immediately initiate the spin of the reels. 20 The "spin reels" button 68 enables the player to initiate the spin of the reels.

The touch screen 46 of the video display 32 also enables the player to change the symbols 54b and 154b. Preferably, when the game displays the "MSG" symbol 54b, and the player 30 desires the "NO MSG" symbol, the game enables the player to touch the area of the display 32 that contains the symbol 54b. The gaming device switches the symbol and provides the associated or accompanying audio and video displays. Likewise, if the player desires to have MSG, the player selects the 35 displayed "NO-MSG" symbol 154b, and the gaming device switches the symbol to the "MSG" symbol.

It should be appreciated that the present invention can operate wherein the video monitor 32 does not contain a touch screen 50. This embodiment requires an extra input device 33 (FIG. 2) similar in form and operation to the cash out button 26 or bet one button 24 described in connection with FIG. 1. The input device toggles through the selections and the video monitor displays the various symbols as they are toggled. The separate input embodiment can toggle through any number of symbols 54, however, it should be appreciated that each selection group or pair (e.g., "MSG"/"NO-MSG") requires its own toggling input. For example, the gaming device can enable the player to toggle both "MSG" or "NO-MSG" and "DOUBLE DRAGON" or "SINGLE DRAGON." In this 50 instance, the gaming device supplies two separate toggle switches.

Referring back to FIG. 4, the invention contemplates a symbol change affecting the symbol 54 selected, all like symbols in a reel 30, all like symbols in a payline 52, all like symbols in the video monitor 32, or all like symbols maintained by the gaming device. For example, in one embodiment, when the player selects the "MSG" symbol 54b on reel 30e, intending to change it to the "NO MSG" symbol 154b, the gaming device only changes that symbol. That is, the other "MSG" symbols 54b displayed on reel 30b are not effected and remain unchanged.

Referring still to FIG. 4, in another embodiment of the present invention, when the player selects either of the "MSG" symbols 54b displayed on reel 30b, intending to 65 change it to the "NO MSG" symbol 154b, the gaming device changes all the "MSG" symbols on that reel. That is, both the "MSG" symbols 54b displayed in paylines 52a and 52c of

reel 30b are changed regardless of which "MSG" symbol the player selects. The "MSG" symbol 54b on reel 30c, however, remains unchanged. The present invention can change all the "MSG" symbols 54b on the entire reel 30b, shown in FIG. 7, or, alternatively, can change only the "MSG" symbols 54b displayed in video monitor 32, i.e., the two shown in paylines 52a and 52b.

Referring to FIG. 6, in a further embodiment of the present invention, when the player selects either of the "MSG" symbols 54b displayed in payline 52b, intending to change it to the "NO MSG" symbol 54d, the gaming device changes all the "MSG" symbols in that payline. That is, both the "MSG" symbols 54b displayed in reels 30d and 30e of the payline 52b are changed regardless of which "MSG" symbol the player selects. The "MSG" symbols 54b on paylines 52a and 52c, however, remain unchanged.

Referring again to FIG. 4, in a still further embodiment of the present invention, when the player selects any of the "MSG" symbols 54b displayed in the video monitor 32, intending to change it to the "NO MSG" symbol 154b, the gaming device changes all the "MSG" symbols displayed in the video monitor. That is, all three of the "MSG" symbols 54b displayed in reels 30b and 30e are changed regardless of which "MSG" symbol the player selects. The present invention can change all the "MSG" symbols 54b on every stop of the gaming machine, shown in FIG. 7, or, alternatively, can change only the "MSG" symbols 54b displayed in video monitor 32, i.e., the three shown in the reels 30b and 30c.

In the above embodiments wherein the gaming device links the symbols 54b or 154b (i.e., the linked payline embodiment, the linked reel embodiment, the linked video screen embodiment, and the linked all stops embodiment), the linked changeable symbols can be in-sink such that they all display the "MSG" symbol 54b or the "NO MSG" symbol 154b at all times. This embodiment is preferred when there are more than two possibilities to choose from for a particular stop that contains a changeable symbol. Alternatively, the present invention can link the changeable symbols so that they all change at one time, but wherein each linked symbol can change to either the "MSG" symbol or the "NO-MSG" symbol.

As briefly described above, the gaming device can enable a player to change any number of symbols in accordance with the gaming device theme and its payout structure. In the examples given above, the present invention contemplates enabling the player to change the "DOUBLE DRAGON" symbol 54c, or other suitable symbol, as well as the "MSG" symbol 54b and the "NO MSG" symbol 54b. In essence, the present invention contains a set of changeable symbols, and the gaming device can assign any symbols of the set to any pay stop on the reels having changeable symbols.

Referring to FIG. 7, to illustrate the multiple selection embodiment, the entire twenty-two stop and five reel array of symbols is displayed. The array contains 110 total stops. Each stop could wind up in one of the three paylines 52a, 52b or 52c after the player spins the reels. Each stop is either changeable or not changeable. In the preferred embodiment, each stop having the "MSG" symbol 54b is changeable and all others are fixed. In one embodiment, the set of possibilities for each changeable symbol includes the "MSG" symbol, which is displayed, or the "NO-MSG" symbol, which would be displayed if the player selected or pressed the area of the touch screen containing the "MSG" symbol 54b.

Alternatively, the present invention can also make the "DOUBLE DRAGON" symbol 54c and the "FORTUNE COOKIE" symbol 54d changeable, so that the set of changeable symbol includes four possibilities. The present invention

can include any number of symbols in the set. It should be appreciated that the changeable symbols could have any indicia and are not limited to the indicia discussed in these examples. The indicia discussed in the examples merely aid in illustrating the present invention. With that understood, the present invention contemplates distributing the symbols or possibilities in a plurality of ways.

In one embodiment, the changeable symbols operate in pairs. For example, the player can toggle back and forth between the "MSG" symbol 54b and the "NO-MSG" symbol 154b or between the "DOUBLE DRAGON" symbol 54c and the "FORTUNE COOKIE" symbol 54d. The pairs preferably operate independently of each other, i.e., selecting "MSG" or "NO-MSG" has no effect upon the "DOUBLE DRAGON" or "FORTUNE COOKIE" symbols and vice-versa.

The pairs can alternatively operate dependently, i.e., selecting "MSG" or "NO-MSG" affects the "DOUBLE DRAGON"/"FORTUNE COOKIE" pair. In this alternative, the gaming device links the pairs so that when, for example 10 the "MSG" symbol appears, the "DOUBLE DRAGON" symbol also appears. If the player selects either one, all "MSG" symbols change to "NO-MSG" symbols and all "DOUBLE DRAGON" symbols change to "FORTUNE COOKIE" symbols. Likewise, selecting either of the "NO-MSG" or "FORTUNE COOKIE" symbols changes these symbols to the "MSG" and "DOUBLE DRAGON" symbols, respectively. This example illustrates a changeable symbol pair linking to one other symbol pair. It should be appreciated that a changeable symbol pair can link to a plurality of different symbol pairs.

In another embodiment, any stop having a changeable symbol enables the player to toggle through all four of the selections. In a further embodiment, any stop having a changeable symbol enables the player to toggle through three 20 of the four selections. It should be appreciated that the present invention contemplates any changeable stop having any number of the possibilities, the determination of which the implementor makes based on the gaming device theme and payout structure.

It is well known that gaming devices having a set of reels that display symbols contain combinations of symbols that yield awards or prizes to the player. The present invention contemplates having such combinations and having one or more symbols of those combinations be changeable symbols. 30 The implementor determines the number of changeable symbols that comprise a winning combination based upon a game theme and upon the payout structure.

For example, the present invention contemplates issuing the player 10 credits for obtaining two "MSG" symbols 54b or 15 credits for obtaining three "NO-MSG" symbols 154b. In this example, the player increases the percentage of obtaining a winning combination by setting all the symbols to display the "MSG" symbols 54b. The player plays for "bigger money" by setting all the symbols to display the "NO-MSG" symbol.

In the embodiment wherein the "DOUBLE DRAGON" symbol 54c and the "FORTUNE COOKIE" symbol 54d are also changeable, the present invention contemplates awarding the player credits for obtaining one of each, i.e. for obtaining an "MSG" symbol, a "NO-MSG" symbol, a "DOUBLE DRAGON" symbol, and a "FORTUNE COOKIE" symbol. In this example, the player maximizes the chances of obtaining this winning combination by setting the changeable stops to have an equal amount of each of the above mentioned symbols.

These examples illustrate that the present invention enables the player to affect the likelihood of obtaining a

11

particular winning combination. The gaming device enables the player to establish personal preferences such as MSG or NO MSG, caffeine or no caffeine, favorite player X or favorite player Y etc., wherein the preferences directly affect the player's success at playing the gaming device. In certain instances, such as changing a symbol to display the logo of a favorite sports team or the name of the player's hometown or city, the selection may vest the player in the outcome of the game. That is, the player desires to win a gaming device award, and the player desires to win the award with the symbols displaying the player's favorite team or city.

While the present invention is described in connection with what is presently considered to be the most practical and preferred embodiments, it should be appreciated that the invention is not limited to the disclosed embodiments, and is intended to cover various modifications and equivalent arrangements included within the spirit and scope of the claims. Modifications and variations in the present invention may be made without departing from the novel aspects of the invention as defined in the claims, and this application is limited only by the scope of the claims.

The invention is hereby claimed as follows:

1. A gaming device operable under control of a processor, said gaming device comprising:

a game controlled by the processor and operable upon a wager by a player;
a plurality of reels in the game;
a plurality of symbols on the reels,

(a) said symbols including a first designated symbol at a designated position on said reels, said first designated symbol selectively displayable as either first indicia or as different second indicia at said designated position on the reels, and

(b) said symbols including a second designated symbol at a different designated position on said reels, said second designated symbol selectively displayable as first indicia or as different second indicia at said designated position on the reels, the first designated symbol and the second designated symbol being the same symbol, the first indicia of the first designated symbol being the same as the first indicia of the second designated symbol,

wherein each of said designated symbols has a function on the reels in the game for determining any winning outcomes;

an input device operable with the processor to enable the player to select which of the first indicia or the second indicia of the first designated symbol will be displayed at the designated position of said first designated symbol on said reels, wherein:

(a) if the player inputs a selection of the first indicia of the first designated symbol on the reels to be displayed at the designated position of said first designated symbol on said reels, the processor causes:

(i) the first indicia of said first designated symbol to be displayed at said designated position of said first designated symbol on the reels, and

(ii) the first indicia of the second designated symbol to be displayed at said designated position of said second designated symbol on the reels, and

(b) if the player inputs a selection of the second indicia of the first designated symbol on the reels to be displayed at the designated position of said first designated symbol on said reels, the processor causes:

(i) the second indicia of said first designated symbol to be displayed at said designated position of said first designated symbol on the reels, and

12

(ii) the second indicia of the second designated symbol to be displayed at said designated position of said second designated symbol on the reels; and at least one winning outcome adapted to be provided to the player based on the symbols generated on said reels and said functions of said symbols regardless of which of said indicia is displayed at the designated position of said designated symbol.

2. The gaming device of claim 1, wherein the input device includes a touch screen.

3. The gaming device of claim 1, wherein the first designated symbol and the second designated symbols are on the same reel.

4. The gaming device of claim 1, wherein the first designated symbol and the second designated symbols are on different reels.

5. The gaming device of claim 1, wherein the second indicia of the first designated symbol is the same as the second indicia of the second designated symbol.

6. The gaming device of claim 1, wherein the second indicia of the first designated symbol is different than the second indicia of the second designated symbol.

7. The gaming device of claim 1, wherein the functions of the first designated symbol and the second designated symbol on the reels in the game are the same for determining any winning outcomes based on the symbols generated on the reels.

8. A gaming device operable under control of a processor, said gaming device comprising:

a game controlled by the processor and operable upon a wager by a player;

a plurality of reels in the game;

a plurality of symbols on the reels, said symbols including a plurality of designated symbols each at different designated positions on said reels, each of said designated symbols selectively displayable on the reels as first indicia or as different second indicia at the designated position of said designated symbol on the reels, and each of said designated symbols having a function on the reels in the game for determining any winning outcomes, at least two of the designated symbols being the same symbol, and the first indicia of one of said same designated symbols being the same as the first indicia of another of said same designated symbols;

an input device operable with the processor to enable the player to select which of the first indicia or the second indicia of one of the plurality of designated symbols will be displayed at the designated position of said designated symbol on said reels, wherein if the player inputs a selection the first indicia or the second indicia of the said designated symbol to be displayed at the designated position of said designated symbol on said reels, the processor causes

(a) the selected first indicia or the selected second indicia of said designated symbol to be displayed on the reels at said designated position on the reels, and

(b) the corresponding first indicia or second indicia for at least one other designated symbol to be displayed on the reels at said designated position of said other designated symbol on the reels; and

at least one winning outcome adapted to be provided to the player based on the symbols generated on said reels regardless of which of said indicia is displayed at the designated position of said designated symbol.

9. The gaming device of claim 8, wherein the input device includes a touch screen.

13

10. The gaming device of claim 8, wherein at least two of said designated symbols are on the same reel.

11. The gaming device of claim 8, wherein at least two of the designated symbols are on different reels.

12. The gaming device of claim 8, wherein the first indicia of each of said same designated symbols are the same and the second indicia of each of said same designated symbols are the same.

13. The gaming device of claim 8, wherein at least two of the designated symbols are different symbols.

14. The gaming device of claim 8, wherein the first indicia of at least two of the designated symbols are different.

15. The gaming device of claim 8, wherein the second indicia of at least two of the same designated symbols are different.

16. The gaming device of claim 8, wherein the functions of a plurality of the designated symbols are the same in the game for determining any winning outcomes based on the symbols generated on the reels.

17. A gaming device operable under control of a processor, said gaming device comprising:

a game controlled by the processor and operable upon a wager by a player;

a plurality of reels in the game;

a plurality of symbols on the reels, said symbols including

a plurality of designated symbols at different designated positions on said reels, each of said designated symbols selectively displayable on the reels as one of a plurality of different indicia at the designated position of said designated symbol on the reels, and each of said designated symbols having a function on the reels in the game for determining any winning outcomes, all of the designated symbols being the same symbol, and one of the plurality of different indicia for each of the designated symbols being the same;

an input device operable with the processor to enable the player to select which of the plurality of different indicia of one of the plurality of designated symbols will be displayed at the designated position of said designated symbol on said reels, wherein if the player inputs a

selection of one of the plurality of indicia of said designated symbol to be displayed at said designated position of said designated symbol on said reels, the processor causes (a) the selected indicia of said designated symbol to be displayed on the reels at said designated position on the reels, and (b) the corresponding indicia for at least one other designated symbol to be displayed on the reels at said designated position of said other designated symbol on the reels; and

at least one winning outcome adapted to be provided to the player based on the symbols generated on said reels and regardless of which of said indicia is displayed at the designated position of said designated symbol.

18. The gaming device of claim 17, wherein the input device includes a touch screen.

19. The gaming device of claim 17, wherein the designated symbols are on the same reel.

20. The gaming device of claim 17, wherein at least two of the designated symbols are on different reels.

21. The gaming device of claim 17, wherein the functions of at least two of the designated symbols are the same in the game for determining any winning outcomes based on the symbols generated on the reels.

22. The gaming device of claim 17, wherein the functions of all of the designated symbols are the same in the game for determining any winning outcomes based on the symbols generated on the reels.

14

23. A gaming device operable under control of a processor, said gaming device comprising:

a game controlled by the processor and operable upon a wager by a player;

a plurality of reels in the game;

a plurality of symbols on the reels,

(a) said symbols including same first and second designated symbols at different designated positions on said reels, each of said first and second designated symbols selectively displayable on the reels as first indicia or as different second indicia at the designated position of said designated symbol on the reels, and

(b) said symbols including same third and fourth designated symbols at different designated positions on said reels, each of said third and fourth designated symbols selectively displayable on the reels as third indicia or as different fourth indicia at the designated position of said designated symbol on the reels,

wherein each of said designated symbols has a function on the reels in the game for determining any winning outcomes;

at least one input device operable with the processor to enable the player to select which of the first indicia or the second indicia of the first designated symbol will be displayed at the designated position of said first designated symbol on said reels, wherein:

(a) if the player inputs a selection of the first indicia of said first designated symbol on the reels to be displayed at the designated position of said first designated symbol on said reels, the processor causes:

(i) the first indicia of said first designated symbol to be displayed at said designated position of said first designated symbol on the reels,

(ii) the first indicia of said second designated symbol to be displayed on the reels at said designated position of said second designated symbol on the reels,

(iii) the third indicia of the third designated symbols to be displayed at the designated position of the third designated symbol on the reels, and

(iv) the third indicia of said fourth designated symbol to be displayed on the reels at said designated position of said fourth designated symbol on the reels, and

(b) if the player inputs a selection of the second indicia of said first designated symbol on the reels to be displayed at the designated position of said first designated symbol on said reels, the processor causes:

(i) the second indicia of said first designated symbol to be displayed at said designated position of said first designated symbol on the reels,

(ii) the second indicia of the second designated symbol to be displayed on the reels at said designated position of said second designated symbol on the reels,

(iii) the fourth indicia of said third designated symbol to be displayed at the designated position of said third designated symbol on the reels, and

(iv) the fourth indicia of said fourth designated symbols to be displayed on the reels at said designated position of said fourth designated symbol on the reels; and

at least one winning outcome adapted to be provided to the player based on the symbols generated on said reels regardless of which of said indicia is displayed at the designated position of each said designated symbol.

24. The gaming device of claim 23, wherein the input device includes a touch screen.

15

25. The gaming device of claim 23, wherein the first and second designated symbols are on the same reel.

26. The gaming device of claim 23, wherein the third and fourth designated symbols are on the same reel.

27. The gaming device of claim 23, wherein at least one of the first and second designated symbols and at least one of the third and fourth designated symbols are on different reels.

28. The gaming device of claim 23, wherein the functions of the first and second designated symbols and the third and fourth designated symbols are different in the game for determining any winning outcomes based on the symbols generated on the reels.

29. A gaming device operable under control of a processor, said gaming device comprising:

a game controlled by the processor and operable upon a wager by a player;

a plurality of reels in the game;

a plurality of symbols on the reels,

(a) said symbols including a first designated symbol at a designated position on said reels, said first designated symbol selectively displayable as first indicia or as different second indicia at said designated position on the reels, and

(b) said symbols including a second designated symbol at a different designated position on said reels, said second designated symbol selectively displayable as first indicia or as different second indicia at said designated position on the reels, the first designated symbol and the second designated symbols being the same symbol, the first indicia of the first designated symbol being the same as the first indicia of the second designated symbol,

wherein each of said designated symbols has a function on the reels in the game for determining any winning outcomes;

means for causing a selection of the display of first indicia or the second indicia for the first designated symbol at the first designated position on said reels, wherein:

(a) if the selection is of the first indicia of the first designated symbol on the reels to be displayed at the designated position of said first designated symbol on said reels, the processor causes:

(i) the first indicia of said first designated symbol to be displayed at said designated position of said first designated symbol on the reels, and

(ii) the first indicia of the second designated symbol to be displayed at said designated position of said second designated symbol on the reels, and

(b) if the selection is of the second indicia of the first designated symbol on the reels to be displayed at the designated position of said first designated symbol on said reels, the processor causes:

(i) the second indicia of said first designated symbol to be displayed at said designated position of said first designated symbol on the reels, and

(ii) the second indicia of the second designated symbol to be displayed at said designated position of said second designated symbol on the reels; and

at least one winning outcome adapted to be provided to the player based on the symbols generated on said reels and said functions of said symbols regardless of which of said indicia is displayed at the designated position of said designated symbol.

30. The gaming device of claim 29, wherein the selection causing means causes a random selection.

16

31. The gaming device of claim 29, wherein the first designated symbol and the second designated symbols are on the same reel.

32. The gaming device of claim 29, wherein the first designated symbol and the second designated symbols are on different reels.

33. The gaming device of claim 29, wherein the second indicia of the first designated symbol is the same as the second indicia of the second designated symbol.

34. The gaming device of claim 29, wherein the second indicia of the first designated symbol is different than the second indicia of the second designated symbol.

35. The gaming device of claim 29, wherein the functions of the first designated symbol and the second designated symbol on the reels in the game are the same for determining any winning outcomes based on the symbols generated on the reels.

36. A gaming device operable under control of a processor, said gaming device comprising:

a game controlled by the processor and operable upon a wager by a player;

a plurality of reels in the game;

a plurality of symbols on the reels, said symbols including a plurality of designated symbols each at different designated positions on said reels, each of said designated symbols selectively displayable on the reels as first indicia or as different second indicia at the designated position of said designated symbol on the reels, and each of said designated symbols having a function on the reels in the game for determining any winning outcomes, at least two of the designated symbols being the same symbol, the first indicia of one of said same designated symbols being the same as the first indicia of another of said same designated symbols;

means for causing a selection of the first indicia or the second indicia of one of the plurality of designated symbols to be displayed at the designated position of said designated symbol on said reels, wherein if the selection is of the first indicia or the second indicia of the said designated symbol to be displayed at the designated position of said designated symbol on said reels, the processor causes

(a) the selected first indicia or the selected second indicia of said designated symbol to be displayed on the reels at said designated position on the reels, and

(b) the corresponding first indicia or second indicia for at least one other designated symbol to be displayed on the reels at said designated position of said other designated symbol on the reels; and

at least one winning outcome adapted to be provided to the player based on the symbols generated on said reels regardless of which of said indicia is displayed at the designated position of said designated symbol.

37. The gaming device of claim 36, wherein the selection causing means causes a random selection.

38. The gaming device of claim 36, wherein at least two of said designated symbols are on the same reel.

39. The gaming device of claim 36, wherein at least two of the designated symbols are on different reels.

40. The gaming device of claim 36, wherein the first indicia of each of said same designated symbols are the same and the second indicia of each of said same designated symbols are the same.

41. The gaming device of claim 36, wherein at least two of the designated symbols are different symbols.

42. The gaming device of claim 36, wherein the first indicia of at least two of the designated symbols are different.

17

43. The gaming device of claim 36, wherein the second indicia of at least two of the designated symbols are different.

44. The gaming device of claim 36, wherein the functions of a plurality of the designated symbols are the same in the game for determining any winning outcomes based on the symbols generated on the reels. 5

45. A gaming device operable under control of a processor, said gaming device comprising:

a game controlled by the processor and operable upon a wager by a player; 10

a plurality of reels in the game;

a plurality of symbols on the reels, said symbols including

a plurality of designated symbols at different designated positions on said reels, each of said designated symbols selectively displayable on the reels as one of a plurality of different indicia at the designated position of said designated symbol on the reels, and each of said designated symbols having a function on the reels in the game

for determining any winning outcomes, all of the designated symbols being the same symbol, and one of the

plurality of different indicia for each of the designated symbols being the same; 15

means for causing a selection of one of the plurality of different indicia of one of the plurality of designated symbols to be displayed at the designated position of

said designated symbol on said reels, wherein after the

selection of one of the plurality of indicia of said designated symbol to be displayed at said designated position

of said designated symbol on said reels, the processor

causes (a) the selected indicia of said designated symbol

to be displayed on the reels at said designated position on

the reels, and (b) the corresponding indicia for at least

one other designated symbol to be displayed on the reels

at said designated position of said other designated symbol on the reels; and 20

at least one winning outcome adapted to be provided to the

player based on the symbols generated on said reels and

regardless of which of said indicia is displayed at the

designated position of said designated symbol. 25

46. The gaming device of claim 45, wherein the selection causing means causes a random selection. 40

47. The gaming device of claim 45, wherein the designated symbols are on the same reel.

48. The gaming device of claim 45, wherein at least two of the designated symbols are on different reels. 45

49. The gaming device of claim 45, wherein the functions of at least two of the designated symbols are the same in the game for determining any winning outcomes based on the symbols generated on the reels.

50. The gaming device of claim 45, wherein the functions of all of the designated symbols are the same in the game for determining any winning outcomes based on the symbols generated on the reels. 50

51. A gaming device operable under control of a processor, said gaming device comprising:

a game controlled by the processor and operable upon a wager by a player; 55

a plurality of reels in the game;

a plurality of symbols on the reels,

(a) said symbols including same first and second designated symbols at different designated positions on

said reels, each of said first and second designated symbols selectively displayable on the reels as first

indicia or as different second indicia at the designated

position of said designated symbol on the reels, and

(b) said symbols including same third and fourth designated symbols at different designated positions on

60

55

60

65

55

60

55

18

said reels, each of said third and fourth designated symbols selectively displayable on the reels as third indicia or as different fourth indicia at the designated position of said designated symbol on the reels, wherein each of said designated symbols has a function on the reels in the game for determining any winning outcomes;

means for causing a selection of the first indicia or the second indicia of the first designated symbol to be displayed at the designated position of said first designated symbol on said reels, wherein:

(a) if the selection is of the first indicia of said first designated symbol on the reels to be displayed at the designated position of said first designated symbol on said reels, the processor causes:

(i) the first indicia of said first designated symbol to be displayed at said designated position of said first designated symbol on the reels,

(ii) the first indicia of said second designated symbol to be displayed on the reels at said designated position of said second designated symbol on the reels,

(iii) the third indicia of the third designated symbols to be displayed at the designated position of the third designated symbol on the reels, and

(iv) the third indicia of said fourth designated symbol to be displayed on the reels at said designated position of said fourth designated symbol on the reels, and

(b) if the selection is of the second indicia of said first designated symbol on the reels to be displayed at the designated position of said first designated symbol on said reels, the processor causes:

(i) the second indicia of said first designated symbol to be displayed at said designated position of said first designated symbol on the reels,

(ii) the second indicia of the second designated symbol to be displayed on the reels at said designated position of said second designated symbol on the reels,

(iii) the fourth indicia of said third designated symbol to be displayed at the designated position of said third designated symbol on the reels, and

(iv) the fourth indicia of said fourth designated symbols to be displayed on the reels at said designated position of said fourth designated symbol on the reels; and

at least one winning outcome adapted to be provided to the player based on the symbols generated on said reels and regardless of which of said indicia is displayed at the designated position of each said designated symbol.

52. The gaming device of claim 51, wherein the selection causing means causes a random selection.

53. The gaming device of claim 51, wherein the first and second designated symbols are on the same reel.

54. The gaming device of claim 51, wherein the third and fourth designated symbols are on the same reel.

55. The gaming device of claim 51, wherein at least one of the first and second designated symbols and at least one of the third and fourth designated symbols are on different reels.

56. The gaming device of claim 51, wherein the functions of the first and second designated symbols and the third and fourth designated symbols are different in the game for determining any winning outcomes based on the symbols generated on the reels.

57. A gaming system comprising:
a gaming device including at least one display device and at least one input device; and

19

a server remote from the gaming device and configured to communicate with said gaming device, said server and said gaming device configured to:

(i) after a player makes a first wager at a first time using said at least one input device,

(a) cause a first random generation of a first plurality of symbols from a first set of symbols, said first set of symbols including a plurality of different symbols,

(b) cause said display device to display said generated first plurality of symbols, and

(c) cause any awards associated with any first winning symbol or symbol combinations of said generated first plurality of symbols to be provided to the player,

(ii) after the player makes an input to change said symbols at a second subsequent time using said at least one input device:

(d) cause a change on the at least one display from the first set of symbols to a second set of symbols, said second set of symbols being different than the first set of symbols, all of the second symbols in said second set of symbols being different than the first symbols in said first set of symbols,

(iii) after the player makes a second wager using said at least one input device,

(e) cause a second random generation of a second plurality of symbols from the second set of symbols which are not in the first set of symbols,

(f) cause said display device to display said generated second plurality of symbols, and

(g) cause any awards associated with any second winning symbols or second winning symbol combinations of said generated second plurality of symbols to be provided to the player, and

such that the server at least in part causes (d).

58. The gaming system of claim **57**, wherein said first set of symbols are on a plurality of first reels.

59. The gaming system of claim **58**, wherein the said second set of symbols are on a plurality of second reels.

60. The gaming system of claim **57**, wherein the said second set of symbols are on a plurality of second reels.

61. The gaming system of claim **57**, wherein the server and said gaming device are configured to: cause said plurality of generated first symbols and the plurality of generated second symbols to be displayed in the same positions by the display device.

62. The gaming system of claim **57**, wherein first winning symbols and first winning symbol combinations and the second winning symbols and second winning symbol combinations are evaluated based on a same payable.

63. The gaming system of claim **57**, wherein first winning symbols and first winning symbol combinations and the second winning symbols and second winning symbol combinations are evaluated based on different paytables.

64. The gaming system of claim **57**, wherein the server at least in part causes at least one of (a), (b), (e), and (f).

65. A gaming device operable under control of a processor, said gaming device comprising:

a game controlled by the processor and operable upon a wager by a player;

a plurality of reels in the game;

a plurality of symbols on the reels,

(a) said symbols including a first designated symbol at a designated position on said reels, said first designated symbol selectively displayable as either first indicia or as different second indicia at said designated position on the reels, and

5

(b) said symbols including a second designated symbol at a different designated position on said reels, said second designated symbol selectively displayable as first indicia or as different second indicia at said designated position on the reels, the first indicia of the first designated symbol being different than the first indicia of the second designated symbol, wherein each of said designated symbols has a function on the reels in the game for determining any winning outcomes;

an input device operable with the processor to enable the player to select which of the first indicia or the second indicia of the first designated symbol will be displayed at the designated position of said first designated symbol on said reels, wherein:

(a) if the player inputs a selection of the first indicia of the first designated symbol on the reels to be displayed at the designated position of said first designated symbol on said reels, the processor causes:

(i) the first indicia of said first designated symbol to be displayed at said designated position of said first designated symbol on the reels, and

(ii) the first indicia of the second designated symbol to be displayed at said designated position of said second designated symbol on the reels, and

(b) if the player inputs a selection of the second indicia of the first designated symbol on the reels to be displayed at the designated position of said first designated symbol on said reels, the processor causes:

(i) the second indicia of said first designated symbol to be displayed at said designated position of said first designated symbol on the reels, and

(ii) the second indicia of the second designated symbol to be displayed at said designated position of said second designated symbol on the reels; and

at least one winning outcome adapted to be provided to the player based on the symbols generated on said reels and said functions of said symbols regardless of which of said indicia is displayed at the designated position of said designated symbol.

66. The gaming device of claim **65**, wherein the input device includes a touch screen.

67. The gaming device of claim **65**, wherein the second indicia of the first designated symbol is different than the second indicia of the second designated symbol.

68. The gaming device of claim **65**, wherein the functions of the first designated symbol and the second designated symbol on the reels in the game are the same for determining any winning outcomes based on the symbols generated on the reels.

50

69. A gaming device operable under control of a processor, said gaming device comprising:

a game controlled by the processor and operable upon a wager by a player;

a plurality of reels in the game;

a plurality of symbols on the reels,

(a) said symbols including a first designated symbol at a designated position on said reels, said first designated symbol selectively displayable as either first indicia or as different second indicia at said designated position on the reels, and

(b) said symbols including a second designated symbol at a different designated position on said reels, said second designated symbol selectively displayable as first indicia or as different second indicia at said designated position on the reels, the first designated symbol and the second designated symbol being different

55

60

65

21

symbols, and the first indicia of the first designated symbol being different than the first indicia of the second designated symbol, wherein each of said designated symbols has a function on the reels in the game for determining any winning outcomes; an input device operable with the processor to enable the player to select which of the first indicia or the second indicia of the first designated symbol will be displayed at the designated position of said first designated symbol on said reels, wherein: (a) if the player inputs a selection of the first indicia of the first designated symbol on the reels to be displayed at the designated position of said first designated symbol on said reels, the processor causes: (i) the first indicia of said first designated symbol to be displayed at said designated position of said first designated symbol on the reels, and (ii) the first indicia of the second designated symbol to be displayed at said designated position of said second designated symbol on the reels, and (b) if the player inputs a selection of the second indicia of the first designated symbol on the reels to be displayed at the designated position of said first designated symbol on said reels, the processor causes: (i) the second indicia of said first designated symbol to be displayed at said designated position of said first designated symbol on the reels, and (ii) the second indicia of the second designated symbol to be displayed at said designated position of said second designated symbol on the reels; and at least one winning outcome adapted to be provided to the player based on the symbols generated on said reels and said functions of said symbols regardless of which of said indicia is displayed at the designated position of said designated symbol.

70. The gaming device of claim 69, wherein the input device includes a touch screen.

71. The gaming device of claim 69, wherein the functions of the first designated symbol and the second designated symbol on the reels in the game are the same for determining any winning outcomes based on the symbols generated on the reels.

72. A gaming device operable under control of a processor, said gaming device comprising:

a game controlled by the processor and operable upon a wager by a player; a plurality of reels in the game; a plurality of symbols on the reels,

(a) said symbols including a first designated symbol at a designated position on said reels, said first designated symbol selectively displayable as either first indicia or as different second indicia at said designated position on the reels, and

(b) said symbols including a second designated symbol at a different designated position on said reels, said second designated symbol selectively displayable as first indicia or as different second indicia at said designated position on the reels,

wherein each of said designated symbols has a function on the reels in the game for determining any winning outcomes, the functions of the first designated symbol and the second designated symbol on the reels in the game being the same for determining any winning outcomes based on the symbols generated on the reels,

22

an input device operable with the processor to enable the player to select which of the first indicia or the second indicia of the first designated symbol will be displayed at the designated position of said first designated symbol on said reels, wherein:

(a) if the player inputs a selection of the first indicia of the first designated symbol on the reels to be displayed at the designated position of said first designated symbol on said reels, the processor causes:

(i) the first indicia of said first designated symbol to be displayed at said designated position of said first designated symbol on the reels, and

(ii) the first indicia of the second designated symbol to be displayed at said designated position of said second designated symbol on the reels, and

(b) if the player inputs a selection of the second indicia of the first designated symbol on the reels to be displayed at the designated position of said first designated symbol on said reels, the processor causes:

(i) the second indicia of said first designated symbol to be displayed at said designated position of said first designated symbol on the reels, and

(ii) the second indicia of the second designated symbol to be displayed at said designated position of said second designated symbol on the reels; and

at least one winning outcome adapted to be provided to the player based on the symbols generated on said reels and said functions of said symbols regardless of which of said indicia is displayed at the designated position of said designated symbol.

73. The gaming device of claim 72, wherein the input device includes a touch screen.

74. The gaming device of claim 72, wherein the first designated symbol and the second designated symbol are the same symbol.

75. The gaming device of claim 72, wherein the first indicia of the first designated symbol is the same as the first indicia of the second designated symbol, and the second indicia of the first designated symbol is the same as the second indicia of the second designated symbol.

76. The gaming device of claim 72, wherein the first designated symbol and the second designated symbol are different symbols.

77. The gaming device of claim 72, wherein the first designated symbol and the second designated symbol are the same symbol, the first indicia of the first designated symbol is the same as the first indicia of the second designated symbol, and the second indicia of the first designated symbol is different than the second indicia of the second designated symbol.

78. A gaming device operable under control of a processor, said gaming device comprising:

a game controlled by the processor and operable upon a wager by a player;

a plurality of reels in the game; a plurality of symbols on the reels, said symbols including

a plurality of designated symbols each at different designated positions on said reels, each of said designated symbols selectively displayable on the reels as first indicia or as different second indicia at the designated position of said designated symbol on the reels, the first indicia of at least two of same designated symbols being different, and each of said designated symbols having a function on the reels in the game for determining any winning outcomes;

an input device operable with the processor to enable the player to select which of the first indicia or the second

indicia of one of the plurality of designated symbols will be displayed at the designated position of said designated symbol on said reels, wherein if the player inputs a selection the first indicia or the second indicia of the said designated symbol to be displayed at the designated position of said designated symbol on said reels, the processor causes

(a) the selected first indicia or the selected second indicia of said designated symbol to be displayed on the reels at said designated position on the reels, and

(b) the corresponding first indicia or second indicia for at least one other designated symbol to be displayed on the reels at said designated position of said other designated symbol on the reels; and

at least one winning outcome adapted to be provided to the player based on the symbols generated on said reels regardless of which of said indicia is displayed at the designated position of said designated symbol.

79. The gaming device of claim 78, wherein the input device includes a touch screen.

80. The gaming device of claim 78, wherein the functions of a plurality of the designated symbols are the same in the game for determining any winning outcomes based on the symbols generated on the reels.

81. A gaming device operable under control of a processor, said gaming device comprising:

a game controlled by the processor and operable upon a wager by a player;

a plurality of reels in the game;

a plurality of symbols on the reels, said symbols including a plurality of designated symbols each at different designated positions on said reels, each of said designated symbols selectively displayable on the reels as first indicia or as different second indicia at the designated position of said designated symbol on the reels, the first indicia of at least two of the designated symbols being different, and each of said designated symbols having a function on the reels in the game for determining any winning outcomes;

an input device operable with the processor to enable the player to select which of the first indicia or the second indicia of one of the plurality of designated symbols will be displayed at the designated position of said designated symbol on said reels, wherein if the player inputs a selection the first indicia or the second indicia of the said designated symbol to be displayed at the designated position of said designated symbol on said reels, the processor causes

(a) the selected first indicia or the selected second indicia of said designated symbol to be displayed on the reels at said designated position on the reels, and

(b) the corresponding first indicia or second indicia for at least one other designated symbol to be displayed on the reels at said designated position of said other designated symbol on the reels; and

at least one winning outcome adapted to be provided to the player based on the symbols generated on said reels regardless of which of said indicia is displayed at the designated position of said designated symbol.

82. The gaming device of claim 81, wherein the input device includes a touch screen.

83. The gaming device of claim 81, wherein the functions of a plurality of the designated symbols are the same in the game for determining any winning outcomes based on the symbols generated on the reels.

84. A gaming device operable under control of a processor, said gaming device comprising:

a game controlled by the processor and operable upon a wager by a player;

a plurality of reels in the game;

a plurality of symbols on the reels, said symbols including a plurality of designated symbols each at different designated positions on said reels, each of said designated symbols selectively displayable on the reels as first indicia or as different second indicia at the designated position of said designated symbol on the reels, and each of said designated symbols having a function on the reels in the game for determining any winning outcomes, the functions of a plurality of the designated symbols being the same in the game for determining any winning outcomes based on the symbols generated on the reels;

an input device operable with the processor to enable the player to select which of the first indicia or the second indicia of one of the plurality of designated symbols will be displayed at the designated position of said designated symbol on said reels, wherein if the player inputs a selection the first indicia or the second indicia of the said designated symbol to be displayed at the designated position of said designated symbol on said reels, the processor causes

(a) the selected first indicia or the selected second indicia of said designated symbol to be displayed on the reels at said designated position on the reels, and

(b) the corresponding first indicia or second indicia for at least one other designated symbol to be displayed on the reels at said designated position of said other designated symbol on the reels; and

at least one winning outcome adapted to be provided to the player based on the symbols generated on said reels regardless of which of said indicia is displayed at the designated position of said designated symbol.

85. The gaming device of claim 84, wherein the input device includes a touch screen.

86. The gaming device of claim 84, wherein at least two of the designated symbols are the same symbol.

87. The gaming device of claim 84, wherein at least two of the designated symbols are different symbols.

88. A gaming device operable under control of a processor, said gaming device comprising:

a game controlled by the processor and operable upon a wager by a player;

a plurality of reels in the game;

a plurality of symbols on the reels, said symbols including a plurality of designated symbols at different designated positions on said reels, each of said designated symbols selectively displayable on the reels as one of a plurality of different indicia at the designated position of said designated symbol on the reels, and each of said designated symbols having a function on the reels in the game for determining any winning outcomes, the functions of at least two of the designated symbols being the same in the game for determining any winning outcomes based on the symbols generated on the reels;

an input device operable with the processor to enable the player to select which of the plurality of different indicia of one of the plurality of designated symbols will be displayed at the designated position of said designated symbol on said reels, wherein if the player inputs a selection of one of the plurality of indicia of said designated symbol to be displayed at said designated position of said designated symbol on said reels, the processor causes (a) the selected indicia of said designated symbol

25

to be displayed on the reels at said designated position on the reels, and (b) the corresponding indicia for at least one other designated symbol to be displayed on the reels at said designated position of said other designated symbol on the reels; and at least one winning outcome adapted to be provided to the player based on the symbols generated on said reels and regardless of which of said indicia is displayed at the designated position of said designated symbol.

89. The gaming device of claim 88, wherein the input device includes a touch screen.

90. The gaming device of claim 88, wherein at least two of the designated symbols are the same symbol.

91. The gaming device of claim 88, wherein all of the designated symbols are the same symbol.

92. The gaming device of claim 88, wherein the functions of all of the designated symbols are the same in the game for determining any winning outcomes based on the symbols generated on the reels.

93. A gaming device operable under control of a processor, said gaming device comprising:

a game controlled by the processor and operable upon a wager by a player;

a plurality of reels in the game;

a plurality of symbols on the reels,

(a) said symbols including a first designated symbol at a designated position on said reels, said first designated symbol selectively displayable as first indicia or as different second indicia at said designated position on the reels, and

(b) said symbols including a second designated symbol at a different designated position on said reels, said second designated symbol selectively displayable as first indicia or as different second indicia at said designated position on the reels, the first indicia of the first designated symbol being different than the first indicia of the second designated symbol,

wherein each of said designated symbols has a function on the reels in the game for determining any winning outcomes;

means for causing a selection of the display of first indicia or the second indicia for the first designated symbol at the first designated position on said reels, wherein:

(a) if the selection is of the first indicia of the first designated symbol on the reels to be displayed at the designated position of said first designated symbol on said reels, the processor causes:

(i) the first indicia of said first designated symbol to be displayed at said designated position of said first designated symbol on the reels, and

(ii) the first indicia of the second designated symbol to be displayed at said designated position of said second designated symbol on the reels, and

(b) if the selection is of the second indicia of the first designated symbol on the reels to be displayed at the designated position of said first designated symbol on said reels, the processor causes:

(i) the second indicia of said first designated symbol to be displayed at said designated position of said first designated symbol on the reels, and

(ii) the second indicia of the second designated symbol to be displayed at said designated position of said second designated symbol on the reels; and

at least one winning outcome adapted to be provided to the player based on the symbols generated on said reels and

26

said functions of said symbols regardless of which of said indicia is displayed at the designated position of said designated symbol.

94. The gaming device of claim 93, wherein the selection causing means causes a random selection.

95. The gaming device of claim 93, wherein the functions of the first designated symbol and the second designated symbol on the reels in the game are the same for determining any winning outcomes based on the symbols generated on the reels.

96. A gaming device operable under control of a processor, said gaming device comprising:

a game controlled by the processor and operable upon a wager by a player;

a plurality of reels in the game;

a plurality of symbols on the reels,

(a) said symbols including a first designated symbol at a designated position on said reels, said first designated symbol selectively displayable as first indicia or as different second indicia at said designated position on the reels, and

(b) said symbols including a second designated symbol at a different designated position on said reels, said second designated symbol selectively displayable as first indicia or as different second indicia at said designated position on the reels, the first designated symbol and the second designated symbol being different symbols,

wherein each of said designated symbols has a function on the reels in the game for determining any winning outcomes;

means for causing a selection of the display of first indicia or the second indicia for the first designated symbol at the first designated position on said reels, wherein:

(a) if the selection is of the first indicia of the first designated symbol on the reels to be displayed at the designated position of said first designated symbol on said reels, the processor causes:

(i) the first indicia of said first designated symbol to be displayed at said designated position of said first designated symbol on the reels, and

(ii) the first indicia of the second designated symbol to be displayed at said designated position of said second designated symbol on the reels, and

(b) if the selection is of the second indicia of the first designated symbol on the reels to be displayed at the designated position of said first designated symbol on said reels, the processor causes:

(i) the second indicia of said first designated symbol to be displayed at said designated position of said first designated symbol on the reels, and

(ii) the second indicia of the second designated symbol to be displayed at said designated position of said second designated symbol on the reels; and

at least one winning outcome adapted to be provided to the player based on the symbols generated on said reels and said functions of said symbols regardless of which of said indicia is displayed at the designated position of said designated symbol.

97. The gaming device of claim 96, wherein the selection causing means causes a random selection.

98. The gaming device of claim 96, wherein the first indicia of the first designated symbol is different than the first indicia of the second designated symbol.

99. The gaming device of claim 96, wherein the functions of the first designated symbol and the second designated

symbol on the reels in the game are the same for determining any winning outcomes based on the symbols generated on the reels.

100. A gaming device operable under control of a processor, said gaming device comprising:

a game controlled by the processor and operable upon a wager by a player;
a plurality of reels in the game;
a plurality of symbols on the reels,

(a) said symbols including a first designated symbol at a designated position on said reels, said first designated symbol selectively displayable as first indicia or as different second indicia at said designated position on the reels, and

(b) said symbols including a second designated symbol at a different designated position on said reels, said second designated symbol selectively displayable as first indicia or as different second indicia at said designated position on the reels,

wherein each of said designated symbols has a function on the reels in the game for determining any winning outcomes, and the functions of the first designated symbol and the second designated symbol on the reels in the game are the same for determining any winning outcomes based on the symbols generated on the reels, means for causing a selection of the display of first indicia or the second indicia for the first designated symbol at the first designated position on said reels, wherein:

(a) if the selection is of the first indicia of the first designated symbol on the reels to be displayed at the designated position of said first designated symbol on said reels, the processor causes:

(i) the first indicia of said first designated symbol to be displayed at said designated position of said first designated symbol on the reels, and

(ii) the first indicia of the second designated symbol to be displayed at said designated position of said second designated symbol on the reels, and

(b) if the selection is of the second indicia of the first designated symbol on the reels to be displayed at the designated position of said first designated symbol on said reels, the processor causes:

(i) the second indicia of said first designated symbol to be displayed at said designated position of said first designated symbol on the reels, and

(ii) the second indicia of the second designated symbol to be displayed at said designated position of said second designated symbol on the reels; and

at least one winning outcome adapted to be provided to the player based on the symbols generated on said reels and said functions of said symbols regardless of which of said indicia is displayed at the designated position of said designated symbol.

101. The gaming device of claim 100, wherein the selection causing means causes a random selection.

102. A gaming device operable under control of a processor, said gaming device comprising:

a game controlled by the processor and operable upon a wager by a player;

a plurality of reels in the game;

a plurality of symbols on the reels, said symbols including a plurality of designated symbols each at different designated positions on said reels, each of said designated symbols selectively displayable on the reels as first indicia or as different second indicia at the designated position of said designated symbol on the reels, the first indicia of at least two same designated symbols being

different, and each of said designated symbols having a function on the reels in the game for determining any winning outcomes;

means for causing a selection of the first indicia or the second indicia of one of the plurality of designated symbols to be displayed at the designated position of said designated symbol on said reels, wherein if the selection is of the first indicia or the second indicia of the said designated symbol to be displayed at the designated position of said designated symbol on said reels, the processor causes

(a) the selected first indicia or the selected second indicia of said designated symbol to be displayed on the reels at said designated position on the reels, and

(b) the corresponding first indicia or second indicia for at least one other designated symbol to be displayed on the reels at said designated position of said other designated symbol on the reels; and

at least one winning outcome adapted to be provided to the player based on the symbols generated on said reels regardless of which of said indicia is displayed at the designated position of said designated symbol.

103. The gaming device of claim 102, wherein the selection causing means causes a random selection.

104. The gaming device of claim 102, wherein at least two of the designated symbols are different symbols.

105. The gaming device of claim 102, wherein the functions of a plurality of the designated symbols are the same in the game for determining any winning outcomes based on the symbols generated on the reels.

106. A gaming device operable under control of a processor, said gaming device comprising:

a game controlled by the processor and operable upon a wager by a player;

a plurality of reels in the game;

a plurality of symbols on the reels, said symbols including a plurality of designated symbols each at different designated positions on said reels, each of said designated symbols selectively displayable on the reels as first indicia or as different second indicia at the designated position of said designated symbol on the reels, the first indicia of at least two designated symbols being different, and each of said designated symbols having a function on the reels in the game for determining any winning outcomes;

means for causing a selection of the first indicia or the second indicia of one of the plurality of designated symbols to be displayed at the designated position of said designated symbol on said reels, wherein if the selection is of the first indicia or the second indicia of the said designated symbol to be displayed at the designated position of said designated symbol on said reels, the processor causes

(a) the selected first indicia or the selected second indicia of said designated symbol to be displayed on the reels at said designated position on the reels, and

(b) the corresponding first indicia or second indicia for at least one other designated symbol to be displayed on the reels at said designated position of said other designated symbol on the reels; and

at least one winning outcome adapted to be provided to the player based on the symbols generated on said reels regardless of which of said indicia is displayed at the designated position of said designated symbol.

107. The gaming device of claim 106, wherein the selection causing means causes a random selection.

108. The gaming device of claim 106, wherein the functions of a plurality of the designated symbols are the same in the game for determining any winning outcomes based on the symbols generated on the reels.

109. A gaming device operable under control of a processor, said gaming device comprising:

a game controlled by the processor and operable upon a wager by a player;
a plurality of reels in the game;
a plurality of symbols on the reels, said symbols including

a plurality of designated symbols each at different designated positions on said reels, each of said designated symbols selectively displayable on the reels as first indicia or as different second indicia at the designated position of said designated symbol on the reels, at least two of the designated symbols being the same, the first indicia of said same designated symbols being the same and the second indicia of at least two of the designated symbols being different and each of said designated symbols having a function on the reels in the game for determining any winning outcomes;

means for causing a selection of the first indicia or the second indicia of one of the plurality of designated symbols to be displayed at the designated position of said designated symbol on said reels, wherein if the selection is of the first indicia or the second indicia of the said designated symbol to be displayed at the designated position of said designated symbol on said reels, the processor causes

(a) the selected first indicia or the selected second indicia of said designated symbol to be displayed on the reels at said designated position on the reels, and
(b) the corresponding first indicia or second indicia for at least one other designated symbol to be displayed on the reels at said designated position of said other designated symbol on the reels; and

at least one winning outcome adapted to be provided to the player based on the symbols generated on said reels regardless of which of said indicia is displayed at the designated position of said designated symbol.

110. The gaming device of claim 109, wherein the selection causing means causes a random selection.

111. The gaming device of claim 109, wherein the functions of a plurality of the designated symbols are the same in the game for determining any winning outcomes based on the symbols generated on the reels.

112. A gaming device operable under control of a processor, said gaming device comprising:

a game controlled by the processor and operable upon a wager by a player;
a plurality of reels in the game;

a plurality of symbols on the reels, said symbols including a plurality of designated symbols each at different designated positions on said reels, each of said designated symbols selectively displayable on the reels as first indicia or as different second indicia at the designated position of said designated symbol on the reels, each of said designated symbols having a function on the reels in the game for determining any winning outcomes, and the functions of a plurality of the designated symbols are the same in the game for determining any winning outcomes based on the symbols generated on the reels;

means for causing a selection of the first indicia or the second indicia of one of the plurality of designated symbols to be displayed at the designated position of said designated symbol on said reels, wherein if the selection is of the first indicia or the second indicia of the said

designated symbol to be displayed at the designated position of said designated symbol on said reels, the processor causes

(a) the selected first indicia or the selected second indicia of said designated symbol to be displayed on the reels at said designated position on the reels, and
(b) the corresponding first indicia or second indicia for at least one other designated symbol to be displayed on the reels at said designated position of said other designated symbol on the reels; and

at least one winning outcome adapted to be provided to the player based on the symbols generated on said reels regardless of which of said indicia is displayed at the designated position of said designated symbol.

113. The gaming device of claim 112, wherein the selection causing means causes a random selection.

114. The gaming device of claim 112, wherein at least two of the designated symbols are the same symbol.

115. The gaming device of claim 112, wherein the first indicia of one of said same designated symbols is the same as the first indicia of another of said same designated symbols.

116. The gaming device of claim 112, wherein the first indicia of each of said same designated symbols are the same and the second indicia of each of said same designated symbols are the same.

117. The gaming device of claim 112, wherein the first indicia of at least two of same designated symbols are different.

118. The gaming device of claim 112, wherein at least two of the designated symbols are different symbols.

119. The gaming device of claim 112, wherein the first indicia of at least two of the designated symbols are different.

120. The gaming device of claim 112, wherein at least two of the designated symbols are the same symbol, the first indicia of the designated symbol are the same, and the second indicia of at least two of the designated symbols are different.

121. A gaming device operable under control of a processor, said gaming device comprising:

a game controlled by the processor and operable upon a wager by a player;

a plurality of reels in the game;
a plurality of symbols on the reels, said symbols including a plurality of designated symbols at different designated positions on said reels, each of said designated symbols selectively displayable on the reels as one of a plurality of different indicia at the designated position of said designated symbol on the reels, each of said designated symbols having a function on the reels in the game for determining any winning outcomes, and the function of at least two of the designated symbols being the same in the game for determining any winning outcomes based on the symbols generated in the reels;

means for causing a selection of one of the plurality of different indicia of one of the plurality of designated symbols to be displayed at the designated position of said designated symbol on said reels, wherein after the selection of one of the plurality of indicia of said designated symbol to be displayed at said designated position of said designated symbol on said reels, the processor causes (a) the selected indicia of said designated symbol to be displayed on the reels at said designated position on the reels, and (b) the corresponding indicia for at least one other designated symbol to be displayed on the reels at said designated position of said other designated symbol on the reels; and

at least one winning outcome adapted to be provided to the player based on the symbols generated on said reels and

31

regardless of which of said indicia is displayed at the designated position of said designated symbol.

122. The gaming device of claim 121, wherein the selection causing means causes a random selection.

123. The gaming device of claim 121, wherein at least two of the designated symbols are the same symbol.

124. The gaming device of claim 121, wherein all of the designated symbols are the same symbol.

125. The gaming device of claim 121, wherein the plurality of different indicia for each of the designated symbols are the same.

126. A gaming system comprising:

a gaming device including at least one display device and at least one input device; and

a server remote from the gaming device and configured to communicate with said gaming device, said server and said gaming device configured to:

(i) after a player makes a first wager at a first time using said at least one input device,

(a) cause a first random generation of a first plurality of symbols from a first set of symbols, said first set of symbols including a plurality of different symbols,

(b) cause said display device to display said generated first plurality of symbols, and

(c) cause any awards associated with any first winning symbol or symbol combinations of said generated first plurality of symbols to be provided to the player,

(ii) after the player makes an input to change said symbols at a second subsequent time using said at least one input device:

(d) cause a change on the at least one display from the first set of symbols to a second set of symbols, said second set of symbols being different than the first set of symbols, said second set of symbols including a plurality of different symbols than said symbols in said first set of symbols, and wherein all of the second symbols in said second set of symbols are different than first symbols in said first set of symbols.

(iii) after the player makes a second wager using said at least one input device,

(e) cause a second random generation of a second plurality of symbols from the second set of symbols which are not in the first set of symbols,

(f) cause said display device to display said generated second plurality of symbols, and

(g) cause any awards associated with any second winning symbols or second winning symbol combinations of said generated second plurality of symbols to be provided to the player, and such that the server at least in part causes (d).

127. The gaming system of claim 126, wherein the server and said gaming device are configured to: cause said plurality of generated first symbols and the plurality of generated second symbols to be displayed in the same positions by the display device.

128. The gaming system of claim 126, wherein first winning symbols and first winning symbol combinations and the second winning symbols and second winning symbol combinations are evaluated based on a same payable.

129. The gaming system of claim 126, wherein first winning symbols and first winning symbol combinations and the second winning symbols and second winning symbol combinations are evaluated based on different paytables.

130. The gaming system of claim 126, wherein the server at least in part causes at least one of (a), (b), (e), and (f).

32

131. A gaming system comprising: a gaming device including at least one display device and at least one input device; and

a server remote from the gaming device and configured to communicate with said gaming device, said server and said gaming device configured to:

(i) after a player makes a first wager at a first time using said at least one input device,

(a) cause a first random generation of a first plurality of symbols from a first set of symbols, said first set of symbols including a plurality of different symbols,

(b) cause said display device to display said generated first plurality of symbols, and

(c) cause any awards associated with any first winning symbol or symbol combinations of said generated first plurality of symbols to be provided to the player,

(ii) after the player makes an input to change said symbols at a second subsequent time using said at least one input device:

(d) cause a change on the at least one display from the first set of symbols to a second set of symbols, said second set of symbols being different than the first set of symbols, said second set of symbols including a plurality of different symbols than said symbols in said first set of symbols,

(iii) after the player makes a second wager using said at least one input device,

(e) cause a second random generation of a second plurality of symbols from the second set of symbols which are not in the first set of symbols,

(f) cause said display device to display said generated second plurality of symbols, and

(g) cause any awards associated with any second winning symbols or second winning symbol combinations of said generated second plurality of symbols to be provided to the player, and

such that the server at least in part causes (d), and

(iv) cause said plurality of generated first symbols and the plurality of generated second symbols to be displayed in the same positions by the display device.

132. The gaming system of claim 131, wherein first winning symbols and first winning symbol combinations and the second winning symbols and second winning symbol combinations are evaluated based on a same payable.

133. The gaming system of claim 131, wherein first winning symbols and first winning symbol combinations and the second winning symbols and second winning symbol combinations are evaluated based on different paytables.

134. A gaming system comprising:

a gaming device including at least one display device and at least one input device; and

a server remote from the gaming device and configured to communicate with said gaming device, said server and said gaming device configured to:

(i) after a player makes a first wager at a first time using said at least one input device,

(a) cause a first random generation of a first plurality of symbols from a first set of symbols, said first set of symbols including a plurality of different symbols,

(b) cause said display device to display said generated first plurality of symbols, and

(c) cause any awards associated with any first winning symbol or symbol combinations of said generated first plurality of symbols to be provided to the player,

(ii) after the player makes an input to change said symbols at a second subsequent time using said at least one input device:

- (d) cause a change on the at least one display from the first set of symbols to a second set of symbols, said second set of symbols being different than the first set of symbols, said second set of symbols including a plurality of different symbols than said symbols in said first set of symbols,
- (iii) after the player makes a second wager using said at least one input device,
- (e) cause a second random generation of a second plurality of symbols from the second set of symbols which are not in the first set of symbols,
- (f) cause said display device to display said generated second plurality of symbols, and
- (g) cause any awards associated with any second winning symbols or second winning symbol combinations of said generated second plurality of symbols to be provided to the player, wherein first winning symbols and first winning symbol combinations and the second winning symbols and second winning symbol combinations are evaluated based on a same payable, and

such that the server at least in part causes (d).

135. The gaming system of claim 134, wherein the server at least in part causes at least one of (a), (b), (e), and (f).

- 136.** A gaming system comprising:
- a gaming device including at least one display device and at least one input device; and
  - a server remote from the gaming device and configured to communicate with said gaming device, said server and said gaming device configured to:
  - (i) after a layer makes a first wager at a first time using said at least one input device,
  - (a) cause a first random generation of a first plurality of symbols from a first set of symbols, said first set of symbols including a plurality of different symbols,
  - (b) cause said display device to display said generated first plurality of symbols, and
  - (c) cause any awards associated with any first winning symbol or symbol combinations of said generated first plurality of symbols to be provided to the player,
  - (ii) after the player makes an input to change said symbols at a second subsequent time using said at least one input device:
  - (d) cause a change on the at least one display from the first set of symbols to a second set of symbols, said second set of symbols being different than the first set of symbols, said second set of symbols including a plurality of different symbols than said symbols in said first set of symbols,
  - (iii) after the player makes a second wager using said at least one input device,
  - (e) cause a second random generation of a second plurality of symbols from the second set of symbols which are not in the first set of symbols,
  - (f) cause said display device to display said generated second plurality of symbols, and
  - (g) cause any awards associated with any second winning symbols or second winning symbol combinations of said generated second plurality of symbols to be provided to the player, and

such that the server at least in part causes (d).

137. The gaming system of claim 136, wherein the server at least in part causes at least one of (a), (b), (e), and (f).

138. A gaming system comprising:

a gaming device including at least one display device and at least one input device; and

a server remote from the gaming device and configured to communicate with said gaming device, said server and said gaming device configured to:

- (i) after a player makes a first wager at a first time using said at least one input device,
- (a) cause a first random generation of a first plurality of symbols from a first set of symbols, said first set of symbols including a plurality of different symbols,
- (b) cause said display device to display said generated first plurality of symbols, and
- (c) cause any awards associated with any first winning symbol or symbol combinations of said generated first plurality of symbols to be provided to the player,
- (ii) after the player makes an input to change said symbols at a second subsequent time using said at least one input device:
- (d) cause a change on the at least one display from the first set of symbols to a second set of symbols, said second set of symbols being different than the first set of symbols, said second set of symbols including a plurality of different symbols than said symbols in said first set of symbols,
- (iii) after the player makes a second wager using said at least one input device,
- (e) cause a second random generation of a second plurality of symbols from the second set of symbols which are not in the first set of symbols,
- (f) cause said display device to display said generated second plurality of symbols, and
- (g) cause any awards associated with any second winning symbols or second winning symbol combinations of said generated second plurality of symbols to be provided to the player, and

such that the server at least in part causes (d), the server and said gaming device being configured to cause said plurality of generated first symbols and the plurality of generated second symbols to be displayed in the same positions by the display device.

139. A gaming system comprising:

- a gaming device including at least one display device and at least one input device; and
- a server remote from the gaming device and configured to communicate with said gaming device, said server and said gaming device configured to:
- (i) after a player makes a first wager at a first time using said at least one input device,
  - (a) cause a first random generation of a first plurality of symbols from a first set of symbols, said first set of symbols including a plurality of different symbols,
  - (b) cause said display device to display said generated first plurality of symbols, and
  - (c) cause any awards associated with any first winning symbol or symbol combinations of said generated first plurality of symbols to be provided to the player,
  - (ii) after the player makes an input to change said symbols at a second subsequent time using said at least one input device:
  - (d) cause a change on the at least one display from the first set of symbols to a second set of symbols, said second set of symbols being different than the first set of symbols, said second set of symbols including a plurality of different symbols than said symbols in said first set of symbols,

35

- (iii) after the player makes a second wager using said at least one input device,
- (e) cause a second random generation of a second plurality of symbols from the second set of symbols which are not in the first set of symbols,
- (f) cause said display device to display said generated second plurality of symbols, and
- (g) cause any awards associated with any second winning symbols or second winning symbol combinations of said generated second plurality of symbols to be provided to the player, and

such that the server at least in part causes (d), the first winning symbols and first winning symbol combinations and the second winning symbols and second winning symbol combinations being evaluated based on a same payable.

140. A gaming system comprising:

- a gaming device including at least one display device and at least one input device; and
- a server remote from the gaming device and configured to communicate with said gaming device, said server and said gaming device configured to:
- (i) after a player makes a first wager at a first time using said at least one input device,

20

- (a) cause a first random generation of a first plurality of symbols from a first set of symbols, said first set of symbols including a plurality of different symbols,
- (b) cause said display device to display said generated first plurality of symbols, and

5

36

- (c) cause any awards associated with any first winning symbol or symbol combinations of said generated first plurality of symbols to be provided to the player,
  - (ii) after the player makes an input to change said symbols at a second subsequent time using said at least one input device:
  - (d) cause a change on the at least one display from the first set of symbols to a second set of symbols, said second set of symbols being different than the first set of symbols, said second set of symbols including a plurality of different symbols than said symbols in said first set of symbols,
  - (iii) after the player makes a second wager using said at least one input device,
  - (e) cause a second random generation of a second plurality of symbols from the second set of symbols which are not in the first set of symbols,
  - (f) cause said display device to display said generated second plurality of symbols, and
  - (g) cause any awards associated with any second winning symbols or second winning symbol combinations of said generated second plurality of symbols to be provided to the player, and
- such that the server at least in part causes (d), the first winning symbols and first winning symbol combinations and the second winning symbols and second winning symbol combinations being evaluated based on different paytables.
